UNITED STATES PATENT OFFICE.

CHARLES L. KINNEY, OF COALINGA, CALIFORNIA, ASSIGNOR TO R. H. HERRON COMPANY, OF LOS ANGELES, CALIFORNIA, A CORPORATION OF CALIFORNIA.

TUBING CATCHER AND SUPPORTER.

1,123,197.

Specification of Letters Patent. Patented Dec. 29, 1914.

Application filed November 17, 1913. Serial No. 801,426.

To all whom it may concern:

Be it known that I, CHARLES L. KINNEY, a citizen of the United States, residing at Coalinga, in the county of Fresno, State of California, have invented new and useful Improvements in Tubing Catchers and Supporters, of which the following is a specification.

This invention relates to a device for catching and supporting a tubing within the casing of an oil well or the like; and the object of the invention is the provision of a simple and effective form of device which may be adjusted in any desired position in the well and which will efficiently support the tubing at any point.

The features particularized in this application have to do with the mounting and action of the casing engaging slips. In my preferred form of device the slips are entirely independent of the frictional anchor which engages the inside of the casing; that is, the expansion and contraction of the slips is independent of the engagement of the casing by the frictional anchor. In my preferred construction I mount a frictional anchor movably around the tubing, the anchor including an upper ring upon which the slips are mounted so that they may move radially; and a spring is employed to contract the slips, which spring is entirely independent of the springs in the friction anchor.

The nature and scope of my invention will be best apparent from the following specification, taken in connection with the preferred form of device shown in the accompanying drawings, in which.

Figure 1 is a view showing the device in its inoperative position, Fig. 2 is a view showing the device in operation and supporting the tubing, Fig. 3 is a cross section taken as indicated by line 3-3 of Fig. 2, Fig. 4 is a cross section taken as indicated by line 4-4 of Fig. 1, Fig. 5 is a cross section taken as indicated by line 5-5 of Fig. 1.

In the drawings the numeral 10 may designate an ordinary casing and 11 may designate a tubing within the casing. At any point on the tubing where it is desired to apply the catcher and supporter I place a coupling or collar 12 which has a larger

diameter at top than at bottom, preferably being in cone shape with vertical channels 55 13 for passage of liquid. One joint of tubing screws downwardly into this collar and another joint screws upwardly in the usual manner. Immediately below the collar 12 and securely attached thereto, is a tube or 60 sleeve 14 which surrounds the tubing immediately beneath the collar. This tube 14 may have apertures 15 at its upper end for circulation of liquid. The tube 14 constitutes the supporting member or foundation 65 upon which the movable parts of my supporter and catcher are mounted.

Mounted about the tube 14 I supply the friction anchor 16. In its preferred form this anchor comprises a lower ring 17, an 70 upper ring 18, and a plurality of bowed spring members 19 adapted to press outwardly against the inside of the casing and to create sufficient friction to support the anchor and the parts supported thereon in 75 any position in the casing—but not sufficient friction to prevent ready movement of the tubing in the casing. The friction anchor is connected with the sleeve 14 through the medium of a pair of pins or studs 20 80 carried by the lower ring 17 and engaging in slots 21. The slots 21 are preferably two in number and located on opposite sides of the sleeve 14 (although the number may be as desired); and each of the slots 21 has a 85 short arm 22 and a long arm 23. By turning the tubing, either the long or short arm of each slot may be brought above the corresponding stud 21. In Fig. 1 the parts are shown in an intermediate position. When 90 the supporter is being lowered into a well, the studs are placed in the short arms 22 of the slots and the frictional engagement of the springs 19 with the casing tends to hold the studs up in these parts of the slot; and 95 the anchor is held in about the relative position shown in Fig. 1. When the tubing has been lowered to its destination, it is raised a few inches (for enough to carry the slots up on the studs so that the lower ends of the 100 slots engage the studs) and the tubing is then turned to bring the long arms of the slots above the stud. The tubing and the sleeve 14 and the cone collar 12 may then be lowered a distance equal to the length of 105 long arms 23 of the slots without moving

the anchor 16 downwardly. This relative movement of the tubing and the anchor causes the expansion of the slips 25 to engage the inside of the casing and support the tubing.

The slips 25 may be of any number, preferably three. They are mounted upon the upper flat face of the ring 18, on a flange 18^a of that ring. The ring carries three headed studs 30 which fit into dove-tailed radial slots 31 in the lower faces of the slips 25, so that the slips may move freely radially on the ring 18. The movement of the slips is entirely independent of the expansion and contraction of the springs 19, the springs 19 merely supporting the ring 18 and being rigidly attached thereto. The slips 25 have grooves 33 in their outer faces, and a circular spring 34 rests in these grooves to normally compress the slips and prevent them from engaging the casing. The slips have the ordinary facial teeth for gripping the casing.

In the normal position of the device, as approximately shown in Fig. 1, the slips are below the cone collar 12. In this position the device is lowered into the casing to the point where it is desired to set the supporter. The tubing is then slightly raised and turned in the direction indicated and then lowered again, when the cone collar 12 moves down into the slips and expands them forcibly against the interior of the casing. The tubing is then rigidly and solidly supported in place. If it is desired to change the position of the supporter it is only necessary to raise the tubing, turn it in the opposite direction until the short arms 22 of the slots come over the studs 21 and then lower or raise the tubing as may be desired. If it is only desired to raise the tubing, it is only necessary to pull upwardly on it, not being necessary to turn the tubing. When the tubing is being raised out of the casing, the studs 21 will be beneath the long arms 23 of the slots; and if the tubing should break and drop, any catcher which is below the break would catch and support the tubing. It is designed that the devices may be placed at the top or bottom of the tubing and in intermediate positions, so that one or several of them may support the entire weight of the tubing. If there are several of the supporters and catchers on a string of tubing, each of the devices only has to support a small portion of the entire weight; and if there is one of the devices on the lowermost joint of tubing it is impossible to drop the tubing in the well while pushing it out, as this catcher will always catch and hold the tubing until the last joint is removed.

I claim—

1. In combination with a well casing and a tubing therein, a slip supporting ring sur-

rounding the tubing, slips mounted directly on and radially slideable on the ring, slip expanding means on the tubing, and an anchor means for the ring frictionally engaging the casing.

2. In combination with a well casing and a tubing therein, a slip supporting ring surrounding the tubing, slips mounted directly on and radially slideable on the ring, slip expanding means on the tubing, and an anchor means for the ring frictionally engaging the casing.

3. In combination with a well casing and a tubing therein, a frictional anchor movably surrounding the tubing and including an upper and a lower ring surrounding the tubing and a plurality of spring members attached to both rings and pressing outwardly against the casing, a plurality of slips mounted directly on the upper ring to slide radially thereon, a slip expanding member on the tubing, and means on the tubing and anchor to hold the anchor and slips from longitudinal movement on the tubing.

4. In combination with a well casing and a tubing therein, a frictional anchor movably surrounding the tubing and including an upper and a lower ring surrounding the tubing and a plurality of spring members attached to both rings and pressing outwardly against the casing, a plurality of slips mounted on the upper ring to slide radially thereon, a spring surrounding the slips to contract them, a slip expanding member on the tubing, and means on the tubing and anchor to hold the anchor and slips from longitudinal movement on the tubing.

5. In combination with a well casing and a tubing therein, a sleeve mounted around the tubing with a slip expanding cone at its upper end, a frictional anchor loosely surrounding the sleeve comprising an upper and a lower ring loosely surrounding the sleeve and flat bowed springs attached terminally to the rings and bearing directly outwardly against the casing, means on the sleeve and the lower ring for locking the anchor longitudinally immovable of the sleeve or to permit said longitudinal movement, headed studs upon the upper ring, casing engaging slips with radial dove-tail slots in their lower surfaces to engage said studs, and a circular spring surrounding the slips to normally contract them.

6. In combination with a well casing and a tubing therein, a sleeve mounted around the tubing with a slip expanding cone at its upper end, a frictional anchor loosely surrounding the sleeve comprising an upper and a lower ring loosely surrounding the sleeve and flat bowed springs attached terminally to the rings and bearing outwardly against the casing, means on the sleeve and

the lower ring for locking the anchor longitudinally immovable of the sleeve or to permit said longitudinal movement, headed studs upon the upper ring, casing engaging slips with radial dove-tail slots in their lower surfaces to engage said studs, said slips also having grooves in their casing engaging faces, and a circular spring surrounding the slips lying in said grooves to

normally contract the slips and prevent engagement with the casing.

In witness that I claim the foregoing I have hereunto subscribed my name this 1st day of November, 1913.

CHARLES L. KINNEY.
